US00D816150S

(12) **United States Design Patent** (10) **Patent No.:** **US D816,150 S**
(45) **Date of Patent:** **** Apr. 24, 2018**

(54) **GIMBAL WITH CAMERA**

(71) Applicant: **SZ DJI Osmo Technology Co., Ltd.**,
Shenzhen (CN)

(72) Inventors: **Ran Liao**, Shenzhen (CN); **Hao Liu**,
Shenzhen (CN); **Min Kim**, Shenzhen (CN);
Dengfeng Hu, Shenzhen (CN);
Yun Zhao, Shenzhen (CN)

(73) Assignee: **SZ DJI Osmo Technology Co., Ltd.**,
Shenzhen (CN)

(**) Term: **15 Years**

(21) Appl. No.: **29/572,781**

(22) Filed: **Jul. 29, 2016**

(51) LOC (11) Cl. **16-05**

(52) U.S. Cl.

USPC **D16/242**

(57) **CLAIM**

The ornamental design for a gimbal with camera, as shown and described.

DESCRIPTION

FIG. 1 is a top, front, right perspective view of a gimbal with camera showing the claimed design;

FIG. 2 is a bottom, rear, left perspective view thereof;

FIG. 3 is a bottom, front, right perspective view thereof;

FIG. 4 is a bottom, front, left perspective view thereof;

FIG. 5 is a front view thereof;

FIG. 6 is a rear view thereof;

FIG. 7 is a right side view thereof;

FIG. 8 is a left side view thereof;

FIG. 9 is a bottom view thereof; and,

FIG. 10 is a top view thereof.

The broken lines in the figures show portions of the gimbal with camera that form no part of the claimed design.

1 Claim, 10 Drawing Sheets
